UNITED STATES PATENT OFFICE.

WALTER S. SHENEFIELD, OF SOUTH BEND, INDIANA.

CONDENSER.

Application filed July 14, 1927. Serial No. 205,656.

My invention relates to condensers and especially to such as are adapted for stills in general, and peppermint stills in particular, although capable of other and analogous uses.

One of the important objects of the invention is to provide a condenser which may be used either as a main condenser or as an auxiliary condenser, in a still or the like, and which will assure of the complete condensation of steam or vapor before it reaches the receiving vat.

Another object of the invention is the provision of a novel and improved structure whereby the steam or vapor entering the condenser will be dispersed over a cooling surface of relatively large area as compared with the size of the condenser.

The invention further contemplates the provision of means for supplying a cooling fluid directly to the portion of the condenser adjacent the steam or vapor inlet to overcome the tendency of the condenser to heat up at this point.

A still further object of the invention is to furnish a device of this character which is simple in construction, relatively inexpensive of manufacture and which can be conveniently installed, the nature of the device being such that it will operate efficiently over a long period of time with little or no attention.

The various features of novelty which characterize the invention are pointed out with particularity in the claims annexed to, and forming a part of this specification. However, for a better understanding of the invention and its objects and advantages, reference should be had to the accompanying drawings which illustrate a preferred embodiment. It is to be understood that the invention is capable of various changes and modifications without departing from the spirit and scope of the subject matter as claimed.

Referring specifically to the drawings, in which similar reference characters designate the same parts in all views,

Fig. 1 is a schematic view in elevation illustrating the application of my invention as a final condenser in a peppermint still;

Fig. 2 is a perspective view of the condenser;

Figure 3 is a central longitudinal sectional view;

Fig. 4 is a horizontal sectional view of the condenser.

Referring specifically to the drawings, Fig. 1 illustrates the peppermint hay container A having the steam inlet pipe 1 at the bottom controlled by a valve 2. The container or tub A is closed by a cover A' and the steam outlet pipe B leads from a point adjacent the top of the tub into the usual main condenser C. The steam outlet pipe B within the condenser C is of serpentine form having a number of coils or convolutions as indicated at C', the pipe decreasing in diameter as usual toward its point of exit at the bottom of the chamber or condenser C. The chamber C is supplied with cold water from storage tank D, through pipe D' which enters chamber C near the bottom. The hot water outlet E is shown at the top of tank C, and a pump (not shown) may be used for effecting a continual circulation of cold water into the tank C.

Inasmuch as the structure above described is old and well known a more detailed description would be superfluous.

Ordinarily in the use of a still as hereinabove described a considerable quantity of peppermint oil is lost, the same passing from the outlet of pipe B as steam, especially after the still has been used for a considerable period without a shut down.

The reason is that it is practically impossible to supply cold water to tank C in sufficient volume to maintain the temperature at a point that would effect a complete condensation of the steam.

I overcome this difficulty by employing the final condenser which is the subject of this invention and which comprehends a vessel 3 which is provided with conical ends and which is supported by a bracket 4 rising from the bottom of a cylindrical vessel 5. The vessel 5 of my improved final condenser is adapted to receive cold water from tank D through an inlet pipe 6 which enters at the bottom and which is controlled by a gate valve 7. The warm water outlet from vessel 5 is shown at 8 as being located just below the top of the vessel.

The peppermint laden steam and fluid passes from the main condenser through pipe B and into the upper end of the inner conical-ended vessel 3 and contacts against the conically shaped water reservoir 9, the walls of which are disposed in closely spaced parallelism with the end wall of vessel 3.

The water reservoir 9 is supplied with water from the lower portion of the vessel 110

5 through tubes 10 which open through the lower conical end of the vessel 3, being there soldered or otherwise sealed to prevent the passage of fluid around their ends, these 5 tubes also serving to support the water reservoir 9. In order to further supply cold water to the upper end of the water reservoir 9, I employ a water pipe 11 leading from the main water pipe 6 and which passes 10 thru the walls of the chambers 3 and 5 and up through the bottom of the reservoir 9 to a point adjacent its conical end. The auxiliary water pipe 11 is controlled by a valve 12 as shown.

15 The conical water reservoir 9 is provided with two radially extending water outlet pipes 13 adjacent its apex for discharging the heated water from the water reservoir 9 into the upper part of the main water vessel 5.

20 From the structure described it will be manifest that the steam and fluid entering the vessel 3 will be disposed over and around the cool wall of the conically shaped water 25 reservoir 9 and will be further cooled by contact with the tubes 10 and auxiliary water pipe 11 so that by the time it reaches the lower end of vessel 3, complete condensation will have been effected. The conical form 30 of the lower portion of the vessel 3 becomes important because it concentrates the fluid and steam residue, if any there be, causing direct engagement thereof with the cold water tubes 10 leading to the reservoir 9.

35 The auxiliary water supply pipe 11 which discharges cold water directly from the inlet 6 at the apex of the conical reservoir 9, is of particular importance since it is perfectly obvious that the apex of reservoir 9 bears the 40 brunt of whatever heat there is in the fluid received from the main condenser pipe B.

The oil passes from the auxiliary condenser through pipe 14 to a vessel 15 which has an oil outlet 15^a and a water outlet 15^b. 45 Vessel 5 is shown provided with a drain cock 16 as shown.

Having thus described the invention, what is claimed is:

1. A condenser comprising a main cold 50 water reservoir, a vessel within said reservoir and having conically shaped ends, a fluid inlet being provided at one end and a fluid outlet provided at the other end, a conically shaped auxiliary water reservoir located in 55 the fluid inlet end of said vessel and having its walls spaced from the conical end wall of said vessel to provide a restricted passage for the fluid therebetween, tubes supporting said conical reservoir and extending through the 60 wall of the lower conical end of said vessel, said tubes providing passages from the lower end of said main water reservoir through the bottom of the auxiliary reservoir for supplying cold water thereto, said auxiliary reservoir having outlet pipes extending laterally 65

through the adjacent wall of said vessel and permitting the circulation of water into the upper end of said main water reservoir, the latter having a cold water inlet at its bottom and a warm water outlet at its top, and an auxiliary cold water inlet pipe leading through the intermediate wall portions of said main water reservoir and vessel and up through the bottom of said auxiliary reservoir, said pipe terminating adjacent the apex of said auxiliary reservoir for subjecting the same to a direct stream of cold water to counteract the effect of the heated fluid at this point. 70

2. In a condenser, a vessel having an inlet and an outlet for the fluid to be condensed; a cooling fluid reservoir in said vessel and spaced from the vessel walls; cooling fluid supply pipes communicating with said reservoir and passing through the wall of said vessel; one of said pipes discharging fluid into said reservoir immediately adjacent said fluid inlet of said vessel and the other at a point remote therefrom; and said pipes being rigidly secured to said reservoir and vessel and supporting the reservoir. 80

3. In a condenser, a vessel having an inlet and an outlet for the fluid to be condensed, a cooling fluid reservoir in said vessel and spaced from the vessel walls; cooling fluid supply pipes communicating with said reservoir and passing through the wall of said vessel; one of said pipes discharging fluid into said reservoir immediately adjacent said fluid inlet of said vessel and the other at a point remote therefrom, said pipes being rigidly secured to said reservoir and vessel and supporting the reservoir, and fluid outlet pipes leading from said reservoir through the wall of said vessel adjacent the vessel inlet. 90

4. A condenser comprising a main cooling fluid reservoir, a vessel within said reservoir and having an inlet and outlet, the vessel being gradually constricted cross sectionally in the direction of said outlet and substantially merging therewith; an auxiliary cooling fluid reservoir within said vessel adjacent its inlet and spaced from its walls, and supply pipes communicating with said auxiliary reservoir and passing through the restricted vessel walls adjacent the vessel outlet whereby the fluid to be condensed will be forced to contact with said pipes adjacent the vessel outlet. 105

5. A condenser comprising a main cooling fluid reservoir, a vessel within said reservoir and having an inlet and outlet the vessel being gradually constricted adjacent said outlet; an auxiliary cooling fluid reservoir within said vessel adjacent its inlet and spaced from its walls; supply pipes communicating with said auxiliary reservoir and passing through the restricted vessel walls adjacent the vessel outlet whereby the fluid to be condensed will be forced to contact with said pipes adjacent the vessel outlet, and auxiliary 120

125

130

means for supplying a jet of cooling fluid directly to the portion of said auxiliary reservoir immediately adjacent said vessel inlet.

6. In a condenser, a vessel having an inlet and an outlet for the fluid to be condensed; a cooling fluid reservoir in said vessel at the inlet end thereof, and a cooling water supply pipe extending from a source of supply thru the wall of said vessel and into said reservoir, the discharge end of said pipe being disposed adjacent the vessel inlet and discharging

7. In a condenser, a vessel having an inlet and an outlet for the fluid to be condensed; a cooling fluid reservoir in said vessel at the inlet end thereof, and a cooling water supply pipe extending from a source of supply thru the wall of said vessel and into said reservoir, the discharge end of said pipe being disposed adjacent the vessel inlet and discharging
